US0D1014442S

(12) **United States Design Patent** (10) **Patent No.:** **US D1,014,442 S**
(45) **Date of Patent:** **** Feb. 13, 2024**

(54) **WIRELESS REMOTE SWITCH**

(71) Applicant: **ABL IP Holding, LLC**, Conyers, GA
(US)

(72) Inventor: **John R. Johnson**, Flowery Branch, GA
(US)

(73) Assignee: **ABL IP HOLDING, LLC**, Conyers,
GA (US)

(**) Term: **15 Years**

(21) Appl. No.: **29/866,437**

(22) Filed: **Sep. 12, 2022**

(51) LOC (14) Cl. **13-03**

(52) U.S. Cl.

USPC **D13/164**

(57) **CLAIM**

The ornamental design for a wireless remote switch, as shown and described.

DESCRIPTION

FIG. 1 is a front view of a wireless remote switch, showing the new design;

FIG. 2 is a rear view thereof;

FIG. 3 is a perspective top right view thereof;

FIG. 4 is a perspective top left view thereof;

FIG. 5 is a perspective bottom right view thereof; and,

FIG. 6 is a perspective bottom left view thereof.

The broken lines in the figures show portions of the wireless remote switch that form no part of the claimed design. The icon and written matter shown in the figures are for illustrative purposes only and form no part of the claimed design.

1 Claim, 6 Drawing Sheets
